SPARK PLUG

Charles Lennig Arnois, Philadelphia, Pa.

Application September 12, 1935, Serial No. 40,234

2 Claims. (Cl. 123—169)

The principal objects of the present invention are to improve the operation of spark plugs and at the same time to prolong their useful lives, to protect the electrode that projects from the insulating sleeve from overheating while providing a sufficiently high temperature but not an excessively high temperature, at and in the neighborhood of the spark gap, to controllably relieve the insulating sleeve from the burden of 5 conducting heat from the electrode that projects from its inner end, and to efficiently use the heat conductivity of the water jacket of the cylinder head for dissipating heat from the spark plug.

Other objects of the invention will appear 10 from the following description at the end of which the invention will be claimed.

Generally stated, the invention consists of a 15 spark plug including a body internally provided with a shoulder and externally provided with a shoulder and externally provided with a thread arranged in proximity with each other for good heat transfer, to the water jacket, said body having a single annular opening at its inner end, and including a shouldered refractory sleeve having 20 an electrode projecting from its inner end; there being provided a second electrode consisting of a gasket seated between said shoulders in proximity with the water jacket and of a ring in proximity with the first mentioned electrode to provide 25 a spark gap and of arms extending from the ring to the gasket and which carry current and also conduct heat from the spark gap to the body thereby lessening the burden of heat conduction imposed on the refractory sleeve to an 30 extent controlled by the size of the arms.

The invention also comprises the improvements 35 to be presently described and finally claimed.

In the following description reference will be 40 made to the accompanying drawing forming part 0 hereof and in which,

Figure 1 is a view principally in central section 45 of a spark plug embodying features of the invention; and

Figure 2 is a perspective view of the electrode 50 which assists the sleeve of refractory material in conducting heat from the neighborhood of the spark gap to the body near the water jacket.

In the drawing, 1 is the body of the plug, and 55 it is provided with a single annular opening 2 at its inner end. Internally the body is provided with a shoulder 3 and externally the body is provided with a thread 4. The thread and the shoulder are arranged in heat conducting proximity with each other and with the water of the jacket 5 of the cylinder head. 6 is a sleeve of refrac-

tory heat conducting and electrically insulating material and it is shouldered as at 7. The sleeve 6 is provided at its inner end with a projecting electrode 8. The other electrode structure comprises a ring 9 in proximity with the electrode 8 to provide a spark gap, and a gasket 10 seated between the shoulders 3 and 7, and arms 11 of which two are shown, but the number and size of the arms 11 are determined by the quantity of heat they are required to conduct from 10 the region of the spark gap to the body and water jacket in order to permit the sleeve 6 to conduct a sufficient quantity of heat to keep the electrode 8 below a temperature that would injure it and at a sufficiently high temperature to 15 insure the presence of a good spark by preventing the deposition of carbon on the electrode.

The hottest part of the device is in a zone surrounding the parts 8 and 9 and the sleeve 6 is very hot, probably hotter than the plug. It is an 20 important feature of the invention that heat be transferred from that zone and dissipated. The coolest region is in the neighborhood of the gasket 10. It is the function of the arms to conduct 25 heat from the zone to the cooler region of the device and for that purpose two things are desirable: first, that good heat conducting contact be made between the arms 11 and the body and this the gasket accomplishes; and second, that the arms be not unduly heated between the zone 30 and region referred to. This is accomplished by keeping the arms out of contact with the sleeve 6, and it is well to keep the arms out of substantial contact with the body 1. The line contact at the inner rim of the opening 2 is 35 negligible.

It will be obvious to those skilled in the art to which the invention relates that modifications may be made in details of construction and in 40 matters of mere form without departing from the spirit of the invention which is not limited to such matters or otherwise than as the prior art and the appended claims may require.

I claim:

1. A spark plug having an electrode structure 45 comprising at its inner end a gasket and at its outer end a ring and current carrying and heat conducting arms connecting the gasket and the ring, in combination with a refractory sleeve having at its inner end a projecting electrode 50 providing with the ring a spark gap, and with a body externally threaded for insertion through the water jacket of a cylinder head, said sleeve and body having shoulders between which the gasket is held in proximity with the thread on 55
